AUTOMATIC FIREARMS FED WITH CARTRIDGES BY MEANS OF FLEXIBLE BELTS, ESPECIALLY FOR USE ON AIRCRAFT

Bernard Maillard, Geneva, Switzerland, assignor to Society "Brevets Aero-Mecaniques," S. A., Geneva, Switzerland, a society of Switzerland

Application July 3, 1952, Serial No. 297,058

Claims priority, application Luxembourg July 10, 1951

6 Claims. (Cl. 89—33.5)

The present invention relates to automatic firearms fed with cartridges assembled to form flexible belts actuated by a feed mechanism working in synchronism with the arm. In the following specification and claims, the expression "automatic firearm" will be used to designate not only the arm proper but also the feed mechanism for actuating the cartridge belt.

The chief object of my invention is to provide a firearm of this kind which is better adapted to meet the requirements of practice than those used up to the present time and in particular which can work at higher rates of firing.

My invention is concerned with automatic firearms including, for the feed of the cartridge belt, two elements, to wit a belt feed mechanism imparting a jerky movement to the end of the belt close to the breech mechanism and auxiliary driving means, located upstream of the first mentioned one, tending to give the belt a more regular feed displacement, advantageously at constant speed. My invention is characterized in that there is further provided, for guiding the cartridge belt between the auxiliary driving means and the belt feed mechanism, a rigid passage, preferably rectilinear and in line with the inlet passage of the firearm proper, the section of this passage being of a height sufficient to enable the belt to fold in zigzag fashion in said passage, the cartridges assuming a staggered disposition therein.

A preferred embodiment of the present invention will be hereinafter described with reference to the accompanying drawings, given merely by way of example, and in which:

Fig. 1 is an end view, partly in section on the line I—I of Fig. 2, of an automatic firearm according to my invention.

Fig. 2 is a plan view corresponding to Fig. 1.

Fig. 3 is a sectional view on the line III—III of Fig. 1.

Fig. 4 is a side view corresponding to Fig. 3.

My invention is concerned with firearms to which the cartridges C are supplied in the form of flexible belts formed for instance by links M assembled together by the cartridges which constitute hinge pins for these links.

The firearm proper A may be of any suitable construction, for instance of the "open breech" type, this arm being preferably mounted slidably in a cradle B (rigid with the aircraft structure), with the interposition of an elastic return system (not visible in the drawing).

The system for supplying cartridges successively to the firearm proper includes, in the conventional manner, a belt feed mechanism P exerting a discontinuous pulling action on the end of said belt close to arm A, this belt feed mechanism being advantageously mounted rigid on cradle B.

It should be noted that belt feed mechanism P may be of any type whatever suitable for feeding cartridges to arm A, for instance of the sliding piece type or of the rotor type, and that it may receive the energy necessary for actuating the cartridge belt either from a source external to the firearm or from a moving part of said fire-

2

arm, this energy being for instance supplied by a portion of the kinetic energy of arm A during its recoil stroke with respect to cradle B.

Such a system, if used alone, has, for relatively great cartridge calibers and for high firing rates, the following drawbacks:

The discontinuous pulling action exerted on the cartridge belt by belt feed mechanism P produces positive and negative accelerations of said belt which are the more important as the caliber of the cartridges is greater and the firing rate higher.

Now this quick succession of accelerations tends to create, in the cartridge belt, in particular due to the elasticity of links M and to the inertia of cartridges C, undulatory movements which may, in certain cases, start from the very inlet of the belt feed mechanism and are always detrimental of a good feed of the cartridge belt toward said belt feed mechanism.

20 The existence of this phenomenon limits the caliber and the rate of firing of automatic firearms fed by means of flexible cartridge belts.

It has already been proposed to limit the development of the disturbing waves to a relatively small portion of the cartridge belt.

25 For instance, for this purpose, the auxiliary belt driving means, working at constant speed, has been connected to the belt feed mechanism through a conduit of variable length formed by a telescopic assembly of elements, the perturbing waves being then limited to the portion of the cartridge belt that is circulating through this conduit, the variations of length of which allow for a gradual damping of said waves.

However, this construction had the disadvantage of 35 introducing between the auxiliary belt driving means and the belt feed mechanism a deformable guiding element the operation of which may be perturbed when high external accelerations occur, which is the case with a firearm mounted on a fighting aircraft.

40 According to my invention, in order to avoid this drawback, I connect the outlet of the auxiliary belt driving means with the inlet of the belt feed mechanism by a rigid passage or conduit 1, preferably rectilinear, the vertical section of which is sufficient to enable the belt 45 to fold in zigzag fashion so that cartridges C assume a staggered disposition inside this conduit, the height *h* of this conduit being for instance about twice the thickness of the belt.

As the section afforded to the belt at the outlet of 50 the auxiliary driving means and at the inlet of the belt feed mechanism is of a height corresponding to the thickness of the belt, rigid conduit 1 is advantageously joined to said auxiliary driving means outlet and belt feed mechanism inlet through oblique wall elements 1a.

55 Furthermore, the system is preferably arranged in such manner that the maximum increase of length of the zig-zag folded portion of the belt (which increase is due to a flattening of this zigzag portion) is at least equal to the length of the sudden displacement imparted to the first cartridge of the belt to engage it into the firearm proper, every time a shot is to be fired.

In other words, rigid passage 1 is so arranged, account being taken of the diameter of the cartridges and of the interval between them, that, the cartridge located at the 60 inlet of said passage being supposed to be stationary, it is possible to give the cartridge located at the outlet end of said passage a displacement of the above mentioned length.

This condition is complied with by suitably choosing 65 the height *h* of conduit 1 and/or the length thereof.

On the other hand, it is advisable not to exceed, for height *h*, the maximum value compatible with a regular

zigzag folded arrangement of the portion of the belt that is being considered, that is to say with an arrangement such that, for the maximum folding of this belt portion, the successive cartridges thereof are bearing alternately against the top and bottom walls of passage 1. Advantageously, these top and bottom walls are provided with projections *b* extending parallel to the axes of the cartridges and intended to facilitate the correct staggered arrangement of said cartridges. It can be seen that the projections restrict the distance between the top and bottom walls of the passage so as to prevent the displacement of the cartridges from the normal order or sequential arrangement thereof. That is to say, the distance between the top and bottom walls of the passage is such that one cartridge cannot pass another cartridge.

With such a construction, only the portion of the belt located in rigid passage 1 will be influenced by the impulses imparted by the belt feed mechanism P.

Furthermore, the relatively loose guiding of this portion of the belt will achieve a damping of the oscillatory effects resulting from the operation of belt feed mechanism P.

Preferably, the auxiliary belt driving means are operated by the energy supplied by the recoil of the firearm proper A with respect to its cradle B.

In the construction illustrated by the drawing, the rigid passage or conduit 1 is carried by the belt feed mechanism P and the actuating elements of the auxiliary belt driving means are constituted by a pair of sprocket wheels 2 keyed on a shaft 3 journaled in two side plates in line with the side walls of passage 1, upstream of said side walls. Side plates 1b carry grooves 4a and 4b respectively, for the guiding of the cartridges (these grooves cooperating respectively with the rear end of the cartridge case and the point of the shells).

A drum 5 journaled on shaft 3 contains a spiral spring 6 the inner end of which is secured to said shaft 3 and the outer end of which is secured to said drum.

A ratchet wheel 7 rigid with said drum cooperates with a holding pawl 8 arranged in such manner that drum 5 can rotate only in the direction corresponding to the displacement, through driving wheels 2, of the cartridge belt toward passage 1.

Ratchet wheel 7 is driven in this direction (indicated by an arrow F) by an oscillating lever 9 pivoting about the axis of shaft 3 and carrying a ratchet arm 10 elastically held in active position by a spring 11, said ratchet arm 10 being arranged to work in the same direction as holding pawl 8, that is to say so as to drive ratchet wheel 7 and drum 5 in the direction of arrow F.

Oscillating lever 9 is actuated by a connecting rod 12 one end of which is pivotally connected to said oscillating lever, for instance about the axis 13 of ratchet arm 10 and the other end of which is pivotally connected to one arm of a lever 14 pivoted at 15 to the frame which carries rigid conduit 1. The other arm of lever 14 is held by a spring 16 in contact with a control cam 17 rigid with the firearm proper A.

The operation of this firearm is as follows:

The arm being ready for firing and spiral spring 6 partly tensioned, the cartridges of the belt fill passage 1, where they are packed in staggered arrangement, the cartridge located in the vertical plane of shaft 3 being engaged in one notch of each of the driving sprockets 2. As soon as the first shot has been fired, the belt feed mechanism P is actuated by the recoil of the firearm and suddenly pulls in the first cartridge C₁, producing a simultaneous displacement toward the firearm proper of the cartridges C₂, C₃, etc. present in passage 1. Due to the recoil of the firearm, cam 17 causes lever 14 to pivot and to drive, through connecting rod 12, ratchet wheel 7 in the direction of arrow F. This wheel in turn drives drum 5 which tensions spiral spring 6 a little more. This increased tensioning of spring 6 has for its effect to drive shaft 3 and wheels 2 which cooperate with

the belt to introduce into rigid passage 1 a new cartridge the presence of which restores the cartridges in said passage to their initial staggered arrangement.

It should be noted that, initially, a certain time will elapse before the whole of the belt is driven at constant speed. During this period, for which the tensioning of spiral spring 6 goes increasing on every shot that is being fired, the belt feed mechanism P can always draw from passage 1 the cartridge necessary for feeding the firearm A. The only consequence of the particular conditions during this starting period will be that the pack of cartridges present in staggered arrangement in passage 1 will be somewhat loosened. When firing is stopped, the belt feed mechanism immediately stops catching cartridges from passage 1 and, under the effect of the residual tension of spring 6 and of the inertia of the belt, driving sprockets 2 will keep rotating for a short time, thus feeding the belt toward passage 1 and stopping only when this passage is again packed.

In a general manner, while I have, in the above description, disclosed what I deem to be practical and efficient embodiments of my invention, it should be well understood that I do not wish to be limited thereto as there might be changes made in the arrangement, disposition and form of the parts without departing from the principle of the present invention as comprehended within the scope of the accompanying claims.

What I claim is:

1. An automatic firearm of the kind in which the cartridges are assembled in the form of a flexible belt which comprises, in combination, a belt feed mechanism for imparting, every time a shot is fired, a jerky movement toward the firearm to the end of the belt close to said firearm, auxiliary belt driving means for imparting a more regular movement in the same direction and at the same rate to a portion of the belt located at a distance from said end thereof, and a rigid passage between said driving means and said mechanism, and the distance between the top and bottom walls of the passage being greater than the thickness of the belt and being restricted so as to prevent the displacement of the cartridges from the sequential arrangement thereof whereby said belt can be packed in zigzag fashion in said passage so that the cartridges are in staggered arrangement therein, the height and length of said rigid passage being such that the difference between the length of belt folded in zigzag fashion in said passage and the length of said passage is at least equal to the length of the sudden displacement imparted by the belt feed mechanism to the first cartridge of the belt to engage it into the firearm proper every time a shot is fired.

2. An automatic firearm according to claim 1 in which the top and bottom walls of the rigid passage are provided with projections in the form of cylindrical sectors having their generatrices parallel to the axes of the cartridges, to facilitate the positioning of the cartridges in staggered arrangement in said rigid passage.

3. An automatic firearm according to claim 1 further including convergent parts to connect the rigid passage to the belt feed mechanism and to the auxiliary belt driving means, said auxiliary belt driving means and belt feed mechanism being arranged to guide the belt in the form of a substantially flat band.

4. An automatic firearm according to claim 1 in which the rigid passage is carried by the belt feed mechanism.

5. An automatic firearm according to claim 1 including a cradle, a firearm proper adapted to recoil with respect to said cradle, and means operative by the kinetic energy of the firearm during its recoil movement for actuating said auxiliary belt driving means.

6. An automatic firearm of the kind in which the cartridges are assembled in the form of a flexible belt which comprises, in combination, a belt feed mechanism for imparting, every time a shot is fired, a jerky movement toward the firearm to the end of the belt close to said

firearm, auxiliary belt driving means for imparting a more regular movement in the same direction and at the same rate to a portion of the belt located at a distance from said end thereof, and a rigid passage between said driving means and said mechanism, the distance between the top and bottom walls of the passage being greater than the thickness of the belt and being restricted so as to prevent the displacement of the cartridges from the sequential arrangement thereof and over most of its length smaller than twice the thickness of said belt whereby said belt can be packed in zigzag fashion in said passage so that the cartridges are in staggered arrangement therein, the auxiliary driving means including a shaft parallel to the line of fire of said firearm, two sprocket wheels adapted to engage the cartridges of the belt, 15 keyed on said shaft, a drum journaled on one of the ends of the shaft, a spiral spring in said drum having its inner end secured to said shaft and its outer end secured to said drum, a ratchet wheel rigid with said drum, pawl means for allowing said drum to rotate only in the direction for which said sprocket wheels drive the cartridge belt toward said rigid passage, an oscillating lever rigid

with said ratchet wheel journaled about said shaft, a ratchet arm adapted to cooperate with said ratchet wheel, this ratchet arm being arranged similarly to said pawl with respect to said ratchet wheel, a connecting rod having one end thereof pivoted to said oscillating lever about the pivot axis of said ratchet arm, a lever pivoted to the rigid passage having one arm pivotally connected to the other end of said connecting rod, a control cam rigid with the firearm proper, and elastic means for keeping the other arm of said last mentioned lever applied against said cam.
